UNITED STATES PATENT OFFICE

NICHOLAS J. CONRAD, OF WILMETTE, ILLINOIS, ASSIGNOR, BY MESNE ASSIGNMENTS, TO SCHWEITZER & CONRAD, INC., OF CHICAGO, ILLINOIS, A CORPORATION OF DELAWARE

FUSED CUT-OUT

Application filed December 21, 1926. Serial No. 156,213.

This invention relates to cut-outs, and more particularly to a fused cut-out specially adapted for subway use.

Cut-outs of this character are commonly positioned in manholes and similar places which are not infrequently flooded with water. It is essential, for this reason, to enclose the cut-out in such a manner as to effectually eliminate all possibility of entry 10 of water when the manhole is flooded. It is also desirable that means be provided whereby the oil container or tank can be readily removed to give easy access to the switch structure and associated parts for inspection and repairs. I accomplish these very desirable results by the novel construction which I employ.

In cut-outs of this general type with which I am familiar the switch structure is more or less permanently associated with the tank and there is no means to prevent opening of the tank or container when the switch is closed. This is objectionable in that the switch cannot be readily removed for repairs 20 and there is danger to the operator if the tank is open with the switch closed. In the construction which I employ the switch can be removed readily from the tank but such removal cannot be effected unless the switch 25 is open. This renders inspection and repair of the switch structure very easy and also protects the operator against carelessness. I also provide means whereby the switch is opened with a snap action, when released, 30 thus preventing the formation of arcs such as would be produced when opening the switch by hand. This feature is of great practical importance as cut-outs of this type are used on high tension lines of 1500 volts and higher. A further important feature of 35 my invention is the provision of means for preventing closing of the switch until after the cover member has been completely assembled and secured in position on the tank. This serves to protect the operator or line-man installing the cut-out in the event that the fuse should blow when the switch is first closed. Further advantages and objects of 40 my invention will appear from the detailed 50 description.

In the drawings:

Figure 1 is a top plan view of a cut-out constructed in accordance with my invention;

Fig. 2 is a front elevation;

Fig. 3 is a section taken substantially on line 3—3 of Fig. 1;

Fig. 4 is a section taken substantially on line 4—4 of Fig. 1;

Fig. 5 is a section taken substantially on line 5—5 of Fig. 1;

Fig. 6 is a section taken substantially on line 6—6 of Fig. 4; and

Fig. 7 is a section taken substantially on line 7—7 of Fig. 4.

My cut-out includes a cylindrical tank 1 of steel or other suitable material to which are secured supporting members or legs 2 of channel cross section and extending below the bottom or lower end 3 of the tank. 70 Bottom 3 is rounded or curved downwardly being of concavo-convex cross section and is provided at its central point with an outlet opening 4 which registers with the bore of the nipple 5 having a base flange 6 at its upper end which is secured by welding, or in any other suitable or preferred manner, to the bottom 3 of the tank. This nipple is normally closed by a pipe plug 7 threaded 75 therein. By removing this plug the oil may 80 be readily drained out of the tank for flushing or cleaning the same.

A steel ring 8 of angle cross section is secured about the upper end portion of tank 1 by welding, or in any other suitable or preferred manner. This ring is provided with spaced bosses 9 which are bored and threaded for reception of suitably spaced cap screws 10 passing through a cover structure 11. These screws serve to removably secure the tank to the cover in depending relation thereto. The cover structure 11 extends rearwardly of the tank and is shaped to provide a supporting bracket 12 of angle 95 cross section provided with suitably spaced openings 13 disposed for reception of hangers by means of which the cut-out can be supported in the manhole. The cut-out is 100 supported on hangers above the floor of the

manhole. The legs 2 are provided for supporting the tank when it is removed.

Bracket 12 is connected at each end to the cover 11 by web element 14, the upper portion of this bracket being also connected by intermediate web elements 15 to a flange 16 extending upwardly from the upper face of cover 11 and defining a rectangular opening. There are two of these openings each forming a continuation of a lower section 17a of a pot-head 17. This lower section depends from cover 11, extending downwardly into the upper portion of tank 1. As will be noted more clearly from Fig. 3, these pot-heads are disposed adjacent the rearward portion of tank 1 and slightly in advance of the bracket 12. Each head includes an upper section 17b having a rectangular base flange 18 seating upon flange 16 and secured thereto by screws 19, or in any other suitable or preferred manner. This construction will be clear from Figs. 1 and 3 of the drawings. Referring more particularly to Fig. 5, each pot-head section 17b is provided with an offset tubular elbow 20, the upper end of which is normally closed by a pipe plug 21 threaded therein. These elbows permit the introduction of a suitable cable sealing compound into the upper sections of the pot-heads after the conductors have been properly installed. An insulating tube 22 of porcelain or other suitable material extends through the lower end of each lower section 17a of the pot-head to within a short distance of the bottom of tank 1. This tube extends upwardly within the pot-head to within a short distance of the upper end thereof and is secured in position by a sealing alloy or composition 23 disposed in the lower pot-head section 17a and tightly securing the tube in the pot-head. These tubes receive conductors 24, each of which is provided with suitable insulation and a lead sheathing 25. This sheath 25 is cut away from the cable from the lower or connection end thereof to within a short distance of the top of the pot-head and is then spread outwardly or flared to provide a bell 26 which fits closely over and about a restricted neck 27 extending from the upper end of the pot-head. This bell is connected to the pot-head by a wiped joint, this joint providing a water tight closure for the upper end of the pot-head about the bell 26 and the neck 27. The upper section 17b of the pot-head thus forms, in effect, a continuation of the sheath 25 of the lead sheath of conductor 24. A suitable packing member or gasket 28 is disposed between flanges 16 and 18 insuring a fluid tight closure between the same. As an additional safeguard, each pot-head above the composition or alloy 23 is filled with a suitable cable sealing compound. This effectively eliminates all possibility of entry of

moisture into the tank through the pot head structure.

The tubes 22, in addition to providing means for accommodating the leads 24, also serve to support the switch mechanism including a supporting and guide frame therefor. This frame includes two guide members 29 of channel cross-section, which are held in spaced parallel relation by cross-bars 30 secured thereto by screw rods 31 and nuts 32 threaded thereon, suitable washers being interposed between the nuts and the guide members 29, the rods 31 passing through members 29 as well as the cross-bars 30. The rods 31 also pass through the end portions of a clamping member or yoke 33 which is bent to fit snugly about tubes 22, the rearward faces of bars 30 being also shaped or recessed to fit snugly about the forward portions of these tubes. Preferably leather 34 or other suitable material is interposed between the tubes 22 and eye 35 of yoke 33 to protect the tube against being broken or cracked. The rods 31 and associated nuts 32 serve to secure the guide members 29 and the cross-bars 30 together in proper relation and also serve to draw the yoke 33 tightly about the tubes 22, thus effectually securing the frame to the tubes in such manner as to be supported thereby with the guide members 29 disposed vertically. A lower cross-bar 36 is secured by screws 37 and nuts 38 to the front faces of the lower ends of guide members 29, these members being provided with front extensions 29a for this purpose. A rectangular contact plate 39 seats upon the upper face of bar 36 between the extensions 29a. This plate has a rearwardly extending finger 40 provided with an opening receiving the screw threaded shank 41 of a cast copper terminal member 42 secured upon the lower end of conductor 24. The other conductor 24 is similarly connected to a contact strip 43 to which is secured one end of a supplemental lead 44 extending through an insulating tube 45 extending through the forward portions of the cross-bars 30. The upper end of this supplemental lead 44 is threaded and receives a nut 46 for establishing close contact between the supplemental lead and a cross strip 47 of copper or other suitable material of high electrical conductivity. This strip is secured at its ends to contact strips 48 which are secured by screws 49 on the upper faces of shoulders 50 formed by cutting away the upper portion of each of the guide members 29 for a portion of its width. This provides a simple and inexpensive construction whereby the switch supporting and guide frame, together with the line contacts and associated parts, are supported by the insulating tubes 22 so as to be entirely free from tank 1, thus permitting ready removal of the

tank when desired. It is also possible, by removing the cover of the tank, to easily expose the entire switch structure for inspection or repairs.

- 5 A rectangular switch plate 50' is slidably mounted in guide members 29 for vertical movement. Fuse clips 51 are secured on the front face of this plate adjacent the top and bottom thereof. These clips include 10 U-shaped members 52 and 53, the arms of the member 52 being bent to provide spring jaws for contact with a fuse terminal and the arms of member 53 opposing outward movement of these jaws. This clip also includes a wire member or bail 54 by means 15 of which the jaws are forced toward each other, this bail acting as a stop member to prevent accidental displacement or withdrawal of the fuse. The construction of 20 the fuse clips is more fully illustrated and described in detail in my co-pending application filed May 25, 1925, Serial No. 32741. These clips provide simple and efficient means whereby a suitable fuse may be readily mounted on the plate 50'.

Switch contact members 55 are engaged by the upper fuse clip and are disposed to contact with the line contacts 50 when the switch plate is in lowered or operative position. The contacts 55 are of laminated construction and are bent downwardly and outwardly of the fuse plate so as to be placed under tension when the plate is in operative position. The outer ends of the leaves of contacts 55 have rubbing contact with the contacts 50 during closing of the switch, thus insuring clean contact surfaces, which is desirable in switches of this type. A lower switch contact 56a is secured to the 35 lower clip and contacts with the lower line contact or plate 39. This lower switch contact is also of laminated construction and is slotted to provide a plurality of contact fingers 56a which are disposed at an inclination downwardly and forwardly of the switch plate (Figs. 3 and 7). The lower portion of plate 50' is slightly reduced in thickness to accommodate the contact 56 and is provided at its lower end with laterally 40 extending ears 57. Eye rods 58 have their lower ends secured to ears 57 and are slideable through screw eyes 59 secured in the outer lateral faces of the guide members 29. Tension springs 60 have their lower ends 45 secured through the eyes at the upper ends of rods 58, the upper ends of these springs being secured through screw eyes 61 secured in guides 29. These springs act to normally hold the switch plate in raised or inoperative position so as to hold the switch contacts out of operative contact with the line contacts. The action of the tension springs 60 in moving the switch plate into raised or inoperative position is supplemented, at the 55 initiation of upward movement of the switch

plate, by the action of the contacts 55 and 56 which, as previously noted, are placed under tension when the switch is closed. In this manner a snap action is obtained in opening the switch which serves to prevent, 70 to a large extent, arcing between the contacts.

A fuse 62 is mounted on the plate 50' and is securely held in position by the fuse clips. This fuse may be of any suitable construction, but is preferably a Schweitzer & Conrad fuse such as that disclosed in my co-pending application for fuse devices and the like, filed April 11, 1923, Serial No. 631,263. This fuse includes an end cap 63 at the upper end of the fuse, this cap being secured 80 in the end of the ferrule of the fuse by a non-hardening cement so as to be blown out when the fuse blows. In my application referred to, the fuse body or barrel is filled with carbon-tetrachloride or a similar liquid. 85 In the present instance, however, the fuse body or barrel is filled with oil similar to that with which the tank is filled so as to prevent mixing with the oil of a different liquid upon blowing of the fuse. A fuse 90 cap retaining member 64 is mounted on the plate above and closely adjacent the upper end of the fuse. This member is preferably of basket-like construction being formed of short wooden bars disposed in spaced relation and secured together. Two arms 65 extend from the front face of fuse plate 50' adjacent the upper end thereof and are connected by a rod 66 upon which is mounted a spacing sleeve 67 of insulating material. 100 This sleeve is disposed adjacent the top of retaining member 64 and serves to prevent escape of the fuse cap therefrom. This arrangement insures that, when the fuse blows, the cap will be retained in member 64 from 105 which it can be readily removed by removing the fuse, permitting the cap to drop out of the retaining member. The fuse is thus mounted upon the board or plate therefor in such manner as to be readily replaced and 110 difficulty in recovering the fuse cap is avoided so as to facilitate replacement of the fuse. This fuse is in series in the circuit, when the switch is closed, and will blow out when the amount of the current equals or exceeds 115 a predetermined maximum acting as a cut-out to prevent injury to the apparatus connected to the line.

The main cover 11 is provided with an upwardly extending flange 68 defining an 120 opening 69 of approximately triangular shape, the rearward portion of this flange also forming the inner walls of the upper portions of the pot-heads 17, that is, the inner walls of the upper portions of the portions 17a of the pot-heads. This opening is closed by a supplemental cover 70 which seats on the front and back portions of the flange 68 and on the upper faces of supplemental flanges 68a extending inwardly from 125 130

the side portions of wall or flange 68. A packing gasket 71 is interposed between the supplemental cover and the main cover, and the supplemental cover is secured in position by cap screws 72 and 73. Screws 72 pass through lugs 74 projecting from supplemental cover 70 and thread through the supplemental lateral flanges 68a. Screws 73 pass through lugs 75 projecting from plate 70 and thread into corresponding lugs 76 projecting from the outer face of the forward portion of flange 68. Each cap screw 71 is provided with a lower reduced portion forming a pin 77 which, when the screw is threaded into full operative position, contacts with the shorter outer arm 78a of an angle latch member 78 rockably mounted on a pin 79 between a pair of ears 80 depending from flange 68a. A leaf spring 81 is secured to the under face of flange 68a and bears against the outer edge of the inner longer arm 78b of the latch so as to urge the arm 78b inwardly. When the latch members are in normal inoperative position, they are out of the path of movement of the upper arms of L-shaped stop members 82 secured to the rearward portions of arms 65 and disposed in the plane of the latch members. When the switch is opened and the switch plate 50' is in raised position, the upper arms of members 82 are disposed above the upper end of arms 78b of the latch members. Under normal conditions, the latch members are held in inoperative position so that the switch can be closed without interference. In the event that the supplemental cover 70 is removed, as when renewing the fuse, the latch members are moved inwardly by the springs 81 into operative position. With the switch open, the members 82 will be disposed above the arms 78b of the latch members and the latch members will prevent the switch from being closed until such time as these latch members are moved into inoperative position by threading the cap screws 71 into their full operative position for securing the supplemental cover 70. This feature is of importance as effectually preventing closing of the switch until such time as the cover 70 is tightly secured in position. This effectually eliminates danger of injury to the operator due to blowing of the fuse when the switch is first closed after removal of the supplemental cover 70 and before replacement thereof.

A switch closing lever 83 is provided for closing the switch. This lever includes rearwardly extending arms 84 pivoted by means of a pintle 85 on members 86 extending from a raised portion or rib 87 at the rearward portion of supplemental cover 70 for reenforcing the same. Arms 84 are connected adjacent their forward ends by a cross piece 88 from which extend forwardly directed arms 89 connected adjacent their outer or

forward ends by a U-shaped stirrup 90. These arms are also connected by a rod 91 secured to the same upon which is mounted a handle 92 of insulating material, this handle also serving as a spacing member for the arms. Each arm 89 is further provided with an upwardly and forwardly extending lug 93 having an opening 94 for reception of a hook or other suitable tool for operating the switch. The lever structure 83 is urged in raised or switch releasing direction by a wire spring 95 coiled about pintle 85, the arms of this spring bearing against rib 87 and the bight portion of the spring being disposed beneath the cross bar 88. Movement of the lever construction in switch opening direction is limited by fingers 96 extending downwardly and rearwardly from the inner ends of arms 84 and disposed to contact with a stop element 87a of rib 87. Cross bar 88 of the switch closing lever is disposed to contact with a plunger 97 operating through a stuffing box 98, mounted in the supplemental cover 70, as the lever is moved into operative position. A spring 99 is mounted on the front portion of the main cover structure and is disposed for engagement with the bight portion 90a of the U-shaped member 90 when the lever is in full operative position. This latch member serves to releasably secure the switch closing lever in lowered position so as to hold the plunger 97 lowered with the head 100 thereof bearing against sleeve 67 and holding the switch plate 50' depressed against the action of the springs 60, maintaining the switch in closed condition. By swinging the latch 99 into inoperative position the switch closing lever is released and is moved by spring 95 into raised or inoperative position. This releases the plunger 97 which is immediately raised by the upward movement of switch plate 50' under the influence of the tension springs 60. This serves to quickly open the switch, as previously described. Upward movement of plunger 97 is cushioned by coil spring 101 disposed about the plunger and resting upon head 100 thereof. Stuffing box 98 is of known construction and I preferably use a water proof packing in this box which serves to exclude water and, at the same time, permits free operation of plunger 97. It will be noted that the plate 50' is moved into and out of switch closing position with a rectilinear movement which I consider advantageous as the room required for operating the switch is reduced to a minimum permitting the use of a relatively small tank while spacing the switch contacts and current carrying parts well away from the walls of the tank.

As will be noted more clearly from Figs. 1 and 2, bight portion 90a of the stirrup 90 is provided, adjacent each end, with a for-

wardly extending lug 102 carrying a depending finger 103. When the switch lever is in operative position, the lower ends of fingers 103 are disposed closely adjacent the heads of the two central cap screws 10 which secure the cover to the flange of ring 8. It will also be noted that bight element 90a is disposed above and closely adjacent the heads of the cap screws 73 securing the forward portion of the supplemental cover 70 to the main cover structure. This renders it impossible to remove either the main cover or the supplemental cover so long as the switch closing lever is depressed or in operative position. In order to remove either of the covers, it is necessary to release the switch closing lever, thus permitting opening of the switch. In this manner I insure that the switch will be opened before either the cover structure or the tank can be removed, thus avoiding the danger of disassembling the cut-out structure with the switch closed. This arrangement, in conjunction with the means previously described for preventing closing of the switch until after the cover structure is tightly secured in position, effectually eliminates danger to the operator due to neglect or carelessness when installing the cut-out.

30. The main cover 11 is further provided, at each side thereof, with a horizontally disposed enlargement or boss 105 which communicates with the space defined by flange 68 and, therefore, with the interior of tank 1. 35. Each of these bosses 105 is interiorly threaded, one boss being closed by a pipe plug 106 and the other boss receiving a pipe 107 threaded therewith. This pipe is connected by piping associated therewith to an air bell positioned adjacent the floor of the manhole. In practice the piping is led upwardly from the cut-out toward the roof of the manhole, being then led downwardly toward the floor with the bell applied to the lower end of 40. the piping. This provides a suitable vent to permit escape of gases from the tank in the event that the fuse blows out, and also serves to effectually prevent the entry of water into the tank in case the manhole is 45. flooded, the air trapped in the bell and piping extending therefrom being compressed as the water rises within the piping and serving to prevent the water from rising within the piping to such a height as to 50. enter tank 1.

While I have illustrated the leads 24 as applied to the cut-out, it will be understood that these leads may be applied in the field. Under ordinary conditions, however, I prefer to have the leads applied as illustrated in the shop or warehouse, leaving a sufficient length of cable beyond the pot-heads to enable the leads to be readily connected to the line when installing the cut-out. This is desirable as avoiding any necessity for open-

ing or in any way disassembling the cut-out and it greatly facilitates installing of the cut-out.

To protect the connections between the contacts and the lower ends of the lead-ins, I preferably provide a wooden barrier or guard plate 108 which is suspended from the lower cross bar 30 by hangers 109, this plate being disposed closely adjacent the lower ends of the lead-ins. This plate 108 serves to guard against accidental contact with live parts when the tank is removed or replaced. The tank 1 preferably has a press board lining 110 which likewise guards the sides of the tank against any accidental contact with live parts. This lining is preferably a loose cylindrical sleeve.

What I claim is:—

1. In a cut-out of the character described, an oil tank, line contacts within the tank, a fuse structure mounted for rectilineal movement into operative relation to the contact, spring means for moving the structure out of operative relation to the contact with a snap action, and means controlled exteriorly of the tank for moving the fuse structure into operative position while the tank remains closed and for retaining it in such position against the action of the spring means.

2. In a cut-out of the character described, an oil tank, a supporting and guide frame within the tank, a fuse plate slidably mounted in the frame, a fuse mounted on the plate, line contacts within the tank, means connecting the fuse in series with said contacts when the fuse plate is moved in one direction into operative position, means urging the fuse plate in the other direction into inoperative position, and means operable exteriorly of the tank for moving the fuse plate into operative position and releasably securing it in such position.

3. In a cut-out of the character described, an oil tank, line contacts within the tank, a fuse plate slidably mounted within the tank, a fuse and fuse contacts carried by the plate, the line contacts being disposed in the path of movement of the fuse contacts with the plate, means operable exteriorly of the tank for moving said plate into contact closing position and for releasably securing it in such position, and means for moving the plate into contact opening position by a snap action when it is released.

4. In a cut-out of the character described, an oil tank, line contacts within the tank, a fuse plate slidably mounted within the tank, a fuse and fuse contacts carried by the plate, the line contacts being disposed in the path of movement of the fuse contacts with the plate, means operable exteriorly of the tank for moving said plate into contact closing position and for releasably securing it in such position, the fuse contacts being placed

under tension when closed and urging the plate in contact opening direction, and means for moving said plate into contact opening position by a snap action when it is released.

5. In a cut-out of the character described, an oil tank, a cover therefor, the tank being removably secured to the cover, cable lead-in tubes secured to the cover and depending therefrom into the tank, a frame supported upon the tubes, a switch carried by the frame and including contacts disposed for connection to cables led through the tubes, and means controlled exteriorly of the tank for closing and opening the switch.

10 6. In a cut-out of the character described, an oil tank, a cover therefor, cable lead-in tubes extending into the tank, line contacts supported from the tubes, a fuse, contacts connected to the fuse terminals, and means controlled exteriorly of the tank for moving the fuse contacts into and out of operative relation to the line contacts.

15 7. In a cut-out of the character described, an oil tank, a cover therefor, cable lead-in tubes extending into the tank, line contacts supported from the tubes, a fuse and contacts connected to the terminals thereof, the fuse and its associated contacts being moveable as a unit to move the fuse contacts into and out of operative relation to the line contacts, and means controlled exteriorly of the tank for moving the fuse and its contacts into and out of circuit closing position.

20 8. In a cut-out of the character described, a cover, a tank removably secured to the cover and depending therefrom, a switch within the tank, a plunger operating through the cover, means cooperating with the plunger for closing the switch upon depression of said plunger, a switch closing member mounted on the cover and movable toward and away from the plunger into and out of contact therewith for closing and releasing the switch, means acting to open the switch, means for releasably holding said member in plunger depressing position, and means carried by the switch closing member preventing removal of the tank when the switch is closed.

25 9. In a cut-out of the character described, a cover, a tank removably secured to the cover and depending therefrom, a switch within the tank, a switch closing member mounted on the upper side of the cover and movable toward and away from the same, means acting to open the switch, means cooperating with said member for closing the switch and holding it closed under pressure when the switch closing member is moved in one direction into operative position, and means releasably securing said switch closing member in operative position.

30 10. In a cut-out of the character described, a cover, a tank removably secured to the

cover and depending therefrom, a switch within the tank, a switch closing member mounted on the upper side of the cover and movable toward and away from the same, means acting to open the switch, means cooperating with said member for closing the switch and holding it closed under pressure when the switch closing member is moved in one direction into operative position, and means on the cover releasably securing said switch closing member in operative position.

11. In a cut-out of the character described, a cover, a tank having a flange at its upper end, set screws passing through the cover and threading into the flange for removably securing the tank to the cover depending therefrom, a switch within the tank, a switch closing member mounted on the outer face of the cover for movement toward and away from the same, means cooperating with said member for closing the switch when the member is depressed, means releasably holding said member depressed, and stop elements carried by the switch closing member and disposed closely adjacent the heads of certain of said set screws preventing removal thereof when said member is depressed, said elements being disposed out of the path of said screws when the switch closing member is raised into inoperative position.

12. In a cut-out of the character described, a cover, a tank removably secured to the cover and depending therefrom, pot-heads carried by the cover, insulating tubes secured in the pot-heads and depending therefrom, the upper ends of the tubes being within the pot-heads, sheathed cables extending through the pot-heads and the tubes, the sheathing of the cables being cut and shaped to extend over the upper ends of the pot-heads, the connections between the cable sheaths and the pot-heads being sealed providing water tight closures, a switch supported from the tubes within the tank, connections between the cables and the line contacts of the switch, and switch operating means controlled exteriorly of the tank.

13. In a cut-out of the character described, a cover, a tank secured to the cover, pot-heads carried by the cover, insulating tubes secured in the pot-heads and depending therefrom, the upper ends of the tubes being within the pot-heads, sheathed cables extending through the pot-heads and the tubes, the sheathing of the cables being cut and shaped to extend over the upper ends of the pot-heads, the connections between the cable sheaths and the pot-heads being sealed providing water tight closures, a switch within the tank, connections between the cables and the line contacts of the switch, and switch operating means controlled exteriorly of the tank.

14. In a cut-out of the character de-

scribed, a main cover, a tank depending from the cover and removably secured thereto, said main cover having an opening, a supplemental cover, a switch within the tank, 5 means controlling operation of the switch exteriorly of the tank, means cooperating with said controlling means for preventing removal of the tank when the switch is closed, and means for securing the supplemental cover to the main cover and preventing closing of the switch after removal of the supplemental cover until after said supplemental cover has been again tightly secured in operative position.

15 15. In a cut-out of the character described, a main cover, a tank depending from the cover and removably secured thereto, said main cover having an opening, a supplemental cover, a switch within the 20 tank, means acting to open the switch, a switch closing lever on the supplemental cover, means cooperating with said lever for closing the switch when the lever is depressed and releasing the switch when the lever is 25 raised, means carried by the lever preventing removal of the tank when said lever is depressed, and means for securing the supplemental cover to the main cover and for preventing closing of the switch until after 30 the supplemental cover is secured tightly in position.

16. In a cut-out of the character described, a main cover, a tank depending from and removably secured to said cover, 35 the main cover having an opening, a supplemental cover for said opening and removably secured to the main cover, a switch within the tank, means acting to open the switch, a switch closing lever on the outer 40 face of the supplemental cover, means cooperating with said lever for closing the switch when the lever is in operative position, means acting to open the switch, means releasably securing the lever in operative 45 position, and means preventing removal of either the tank or the supplemental cover when the switch is closed.

17. In a cut-out of the character described, a main cover, a tank depending from and removably secured to said cover, the main 50 cover having an opening, a supplemental cover for said opening and removably secured to the main cover, a switch within the tank, means for controlling the operation of the switch exteriorly of the tank, and means associated with said controlling means for preventing removal of either the tank or the supplemental cover when the switch is closed.

60 18. In a cut-out switch of the character described, a supporting and guide frame, a plate slidably mounted in said frame, contact members on the frame, a fuse on the plate, contact members on the plate disposed 65 to contact with the members on the frame

when the plate is moved in one direction, the plate contact members being connected to the terminals of the fuse, and means acting to move the plate in the other direction opening the switch.

70 19. In a cut-out switch of the character described, a supporting and guide frame, a plate slidably mounted in said frame, contact members on the frame, fuse clips on the plate, contact members connected to the clips and disposed for contact with the frame contact members upon movement of the plate in one direction, a fuse mounted in said clips, and means acting to move the plate in the other direction opening the 75 switch.

80 20. In a cut-out switch of the character described, two members connected for relative sliding movement, cooperating contacts carried by said members and moved into and out of operative relation by relative movement of the members toward and away from each other, a fuse carried by one of said members and disposed in series with the contacts thereof, and means acting to cause relative movement of the members away from each other.

85 21. In a cut-out switch of the character described, two members connected for relative sliding movement, cooperating contacts carried by said members and moved into and out of operative relation by relative movement of the members toward and away from each other, and means acting to cause relative movement of said members away 90 from each other.

95 22. In a cut-out switch of the character described including a plate and a fuse mounted thereon and having a blowout closure member at one end, a closure member retaining structure mounted on the plate adjacent said end of the fuse and in alignment therewith to receive and retain said closure member.

100 23. In a cut-out, a tank, a removable cover therefor, cable lead-in tubes secured to the cover and depending therefrom into the tank, a supporting and guide frame secured to said tubes, line contacts mounted on the frame, a fuse plate slidably mounted in the frame, a fuse and contacts connected to the terminals thereof, the fuse and its contacts being mounted on the fuse plate and the fuse contacts being movable into and out of operative relation to the line contacts in accordance with movement of the plate, and means for moving the fuse plate into circuit closing position and circuit opening position.

110 In witness whereof I hereunto subscribe 125 my name this 15th day of December, 1926.

NICHOLAS J. CONRAD.
